(57) **CLAIM**

I claim the ornamental design for an athletic and travel bag, as shown and described.

DESCRIPTION

FIG. 1 is a front and top perspective view of the athletic and travel bag with the zippered pockets in the closed position;

FIG. 2 is a front and top perspective view of the athletic and travel bag with the zippered pockets in the opened position, and showing the inner transparent bag pulled out of one side section of the athletic and travel bag;

FIG. 3 is a side elevation view of the right side of the athletic and travel bag;

FIG. 4 is a side elevation view of the left side of the athletic and travel bag;

FIG. 5 is a top plan view of the athletic and travel bag;

FIG. 6 is a bottom view of the athletic and travel bag;

FIG. 7 is a front elevation view of the athletic and travel bag;

FIG. 8 is a rear elevation view of the athletic and travel bag;

FIG. 9 is a front elevation view of the athletic and travel bag showing the zippered pockets in the open position; and,

FIG. 10 is a side elevation view of the left side of the athletic and travel bag showing the zippered pockets in the open position, with the left side of the athletic and travel bag showing the zippered pockets in the open position being a mirror image of same.
